C. D. PLATT

ELECTRIC CUT-OUT AND THE LIKE

Filed April 8, 1922

INVENTOR
C. O. Platt
BY
K. J. Flynn
ATTORNEY

UNITED STATES PATENT OFFICE.

CLARENCE D. PLATT, OF BRIDGEPORT, CONNECTICUT.

ELECTRIC CUT-OUT AND THE LIKE.

Application filed April 8, 1922. Serial No. 550,562.

To all whom it may concern:

Be it known that I, CLARENCE D. PLATT, a citizen of the United States of America, residing at Bridgeport, Conn., have invented 5 a new and useful Electric Cut-Out and the like, of which the following is a specification.

Devices of this character are frequently so constructed that the circuit terminals are 10 covered or protected by removable covers through which the fuse or other screw base is adapted to be inserted. With such devices the workman who is wiring the device frequently fails to secure the cover in place 15 when the wiring is completed. This results in leaving the circuit terminals exposed.

To avoid these difficulties I have secured the screw shell or socket to the cap or cover 20 so that the workman must replace the cap or cover in order to make the device operative and to insert the fuse plug.

Fig. 1 is a plan view of one form of cut-out embodying the improvements of my invention, one of the covers being omitted and 25 one set of terminals being omitted.

Fig. 2 is a cross section of the same on the plane of the line 2—2 of Fig. 1, but with all 30 the terminals in place and one of the covers omitted.

Fig. 3 is an exploded perspective showing the parts for the connection of one fuse plug 35 and the like.

Figs. 4 and 5 are cross sectional views showing modified means for securing screw shells in caps.

The base 6 is usually of insulating material of such shape as the particular conditions of use require. The terminals 7 and 8 40 may be of any suitable design or construction. The cover 9 will be shaped to suit the particular conditions of use.

The particular construction illustrated is intended to accommodate fuse plugs of 45 standard type and for this purpose there will be a center contact 10 in the form of a screw connected to the terminal 7 by a member 11. The screw shell or socket 12 adapted to receive the threaded part of an ordinary plug is carried by the insulating cap 9 50 and may be held in place, for instance, by flanges 13 and 14 to prevent longitudinal displacement and a lug 15 extending into a recess 16 to prevent relative rotation. The base 6 is provided with a stationary metallic 55 socket adapted to receive the lower end of the screw shell 12. This socket has a base

flange 17 and spring fingers 18 which are preferably flared outward slightly to receive the tapered or rounded end of the screw shell 12. The terminal 8 is provided with an extension plate or foot 19 adapted to overstand the flange 17, and this plate 19 is provided with a central opening 20 to allow for the shank of the screw 10. An insulating washer 22 is interposed between the plate 19 and the flange or washer 23 beneath the head of the screw 10. The base 6 is preferably provided with a recess 24 to accommodate the socket and the terminal 8. The base in this case is also provided with a groove 25 to accommodate the conductor leading to terminal 7. The cover may be secured in place by one or more screws such as 26.

When it is desired to wire the cut-out the 75 cover is removed and the wires connected to the terminals 7 and 8 in the usual manner. When the cover is removed there is no way of fastening a standard fuse plug or other 80 similar device in place. The deficiency is so obvious that workmen will notice it and must properly complete the work by attaching the cover where it belongs.

It should be understood that the screw shell 12 may be fastened to the cover in 85 many different ways, for instance, as shown in Fig. 4. The cover 30 has an opening to receive the screw shell 31. One end of the screw shell is flared at 32 to form an abutment to cooperate with the lower side of the 90 cover. The lug 33 is forced outward from the side of the screw shell to fit in a groove 34 and prevent rotation as well as longitudinal displacement.

In the form shown in Fig. 5 the cover 35 95 is provided with a threaded passage into which the screw shell 36 is screwed. One end of the screw shell may be provided with a shoulder 37 to limit the inward movement. The other end of the screw shell is provided 100 with a lip or lug 38 pressed outward into a groove 39 so as to prevent the screw shell from being unscrewed from the cover 35 after it is once in position.

I claim:

1. In a cut-out, an insulating base, a socket secured to said base, a center contact, circuit terminals carried by said base and connected to said socket and said center contact, a detachable cover and a screw shell carried 110 thereby adapted to engage said socket.
2. In an electric cut-out, a base, a yielding

105

socket carried thereby, a center contact insulated from said socket, a detachable cover, a screw shell carried by said cover having means for engaging said socket.

5 3. In an electric cut-out, a base, a socket carried thereby, a center contact insulated from said socket, a detachable cover, and a screw shell carried by said cover and having a tapered end adapted to be seated in said

10 socket.

4. In an electric cut-out, an insulating base, a socket carried thereby and having yielding fingers, a detachable cover, a screw shell carried by said cover having an end 15 adapted to engage said yielding fingers.

5. In a cut-out, an insulating base having a recess, a socket mounted in said recess, a circuit terminal connected to said socket, a center contact mounted within said socket 20 but insulated therefrom, a line terminal connected to said center contact, a detachable cover and a fuse receiving member carried by said cover and adapted to engage said socket.

25 6. In an electric cut-out, an insulating base having a recess, a socket mounted in said recess, a center contact mounted within said socket but insulated therefrom, a detachable cover, a screw shell mounted in said cover

and having a projecting end adapted to engage said socket.

7. In an electric cut-out, an insulating base having a recess, a socket mounted therein having a flaring mouth, a detachable cover, a screw shell carried thereby having a tapered 35 end adapted to engage in the flaring mouth of said socket.

8. In an electric cut-out, an insulating base having a recess therein, a socket mounted in said recess, a center contact mounted within 40 said socket but insulated therefrom, a detachable cover, a screw shell carried thereby having an end adapted to engage said socket and means for preventing rotation of said screw shell.

9. A cut-out comprising an insulating base, a center contact for a fuse plug, a second contact disposed laterally thereof, circuit terminals connected to said contacts, an insulating cover detachably secured to said 50 base and having an opening in line with said center contact and a screw shell for a fuse plug carried by said cover in said opening and in electrical engagement with said second contact when the cover is secured in 55 place and removable with said cover.

CLARENCE D. PLATT.
